[57] CLAIM

The ornamental design for a telephone base and stand, as shown and described.

DESCRIPTION

FIG. 1 is a front elevational view of the telephone base and stand showing my new design;

FIG. 2 is a rear elevational view thereof;

FIG. 3 is a top plan view thereof;

FIG. 4 is a bottom plan view thereof;

FIG. 5 is a left-hand side view thereof;

FIG. 6 is a right-hand side view thereof; and,

FIG. 7 is a front elevational view thereof.

The broken line showings in FIGS. 1,2,3,4,5 and 7 are for illustrative purposes only and form no part of the claimed design.
